UNITED STATES PATENT OFFICE.

ROBERT KROEDEL, OF ROCHESTER, NEW YORK, ASSIGNOR TO EASTMAN KODAK COMPANY, OF ROCHESTER, NEW YORK, A CORPORATION OF NEW YORK.

DEVELOPING APPARATUS FOR PHOTOGRAPHIC FILMS.

1,270,302.

Specification of Letters Patent. Patented June 25, 1918.

Application filed April 26, 1917. Serial No. 164,664.

To all whom it may concern:

Be it known that I, ROBERT KROEDEL, of Rochester, in the county of Monroe and State of New York, have invented certain new and useful Improvements in Developing Apparatus for Photographic Films; and I do hereby declare the following to be a full, clear, and exact description of the same, reference being had to the accompanying drawings, forming a part of this specification, and to the reference-numerals marked thereon.

My present invention relates to photography and more particularly to photographic film development and it has for its object to provide a simple, efficient and cheap form of developing apparatus adapted for use by amateurs in the development of the ordinary roll film cartridge of commerce though features thereof are applicable to the development of film strips generally. To these and other ends the invention resides in certain improvements and combinations of parts all as will be hereinafter more fully described, the novel features being pointed out in the claims at the end of the specification.

In the drawings:

Figure 1 is a top plan view of a developing device constructed in accordance with and illustrating one embodiment of my invention;

Fig. 2 is a side view thereof;

Fig. 3 is a bottom plan view of the film supporting member with a film strip in place therein;

Fig. 4 is a bottom plan view of the film supporting member with the film removed and the roll holding box removed;

Fig. 5 is a side view of the film supporting member;

Fig. 6 is an enlarged longitudinal central section taken vertically through the device with the center portion thereof broken away;

Fig. 7 is a transverse sectional view taken substantially on the line 7—7 of Fig. 6;

Fig. 8 is a transverse sectional view taken substantially on the line 8—8 of Fig. 6, and

Fig. 9 is an end view of the film supporting member.

Similar reference numerals throughout the several views indicate the same parts.

In the present embodiment of the invention, the apparatus is made mainly of wood, 55 preferably suitably treated with oil or wax

to reduce its absorptive characteristics. It comprises two major parts, a long rectangular shallow tray 1 and an elongated film supporting member or block 2 fitting within the tray. The member 2 has a reduced portion 3 at one end adjacent to a semi-cylindrical concavity 4 in the end face of the block and this concavity is adapted to receive a film roll wound on the usual film spool 5. The roll is held within the concavity by a detachable box 6 that fits telescopically over the reduced portion 3 and provides a light-tight roll holding chamber 7 at this end of the film supporting member. Shoulders 8 at the base of the reduced portion 3 define the correct position of the box 6. At its opposite end the film support 2 is provided with a receding or inclined end face 9 that engages under an undercut end wall 10 of the tray 1. The support 2 is inserted in the tray by first engaging its end 9 in the undercut portion 10 and then lowering the opposite end to position. This arrangement tends to lock the two parts together, prevents the ready entrance of light to the bottom of the tray and further serves as a clamping means for the free end of a film strip as will be later described.

Communicating with the roll holding chamber 7 are two inclined guides 11 formed by converging flanges or shoulders 12 on the bottom of the film supporting member 2. Between and above the guides the member 2 is hollowed out by the formation of a channel 13 on its under side that extends the length thereof with the exception of solid portions 14 and 15 at respective ends that provide short lengths of wall opposed in spaced relation to the walls 12 of the film guides 11. A tortuous passage 16 extending longitudinally and transversely through the member 2 terminates at the top or upper face of the member in a pour opening 17 and at its other or lower end in a discharge opening 18 that delivers to the channel 13 and permits developing liquid to be introduced therein without admitting any appreciable amount of light.

In using the device, the box 6 is removed and the film roll, consisting of the film strip 19 and the backing strip 20, is inserted in the concavity 4. The box is then replaced to properly confine the roll after leading the outer or advance end of the film and its backing into the guides 11. The strips are

thereafter drawn along the guides until the film 19 is disposed from end to end of the support 2 and below the channel 13 and the extremity of the backing strip 20 is brought 5 around, as shown in Fig. 6 and clamped between the undercut wall 10 of the tray and the end face 9 of the support as the latter is inserted in the former. The bottoms of the guides 11 are separated a distance less 10 than the width of the film strip for which the device is adapted and as before stated, these guides are inclined downwardly with the result that the film is held by its edges only in a downwardly curved position as best 15 shown in Fig. 7. The tension of the strips when thus distorted holds them tightly in the guides against the entrance of light from below and provides a curved bottom for the channel 13. The loading of the film into 20 the device is accomplished in a dark room but the further operations may be performed in the light.

The developing fluid is now poured into the opening 17 and through the passage 16 25 to the channel 13 which it fills in direct contact with the upper sensitized surface of the film 19 which latter is thus developed, a rocking motion preferably being communicated to the tray, as usual.

30 The solid portions 14 and 15 at the ends of the channel 13 serve to prevent the stretched film strip from sagging downward or doubling sufficiently to become detached from the guides, particularly when 35 inserting the support 2 in the tray 1 and it will be noted that during the process of developing, the sensitive or emulsion surface of the film is turned upward with the body of developer above it so that there 40 is little tendency for air bubbles to adhere thereto.

I claim as my invention:

1. In a roll film developing apparatus, the combination with a support provided with 45 film retaining guides and a roll holding box detachably coöperating with one end of the

support to form a roll holding chamber communicating with said guides, of a developing tray adapted to receive the support and to retain the roll holding box in place thereon. 50

2. In a roll film developing apparatus, the combination with a support provided with film retaining guides and a roll holding box detachably coöperating with one end of the support to form a roll holding chamber 55 communicating with said guides, the opposite end of the support having an inclined face, of a developing tray adapted to receive the support and to retain the roll holding box in place thereon, one end of the tray 60 being provided with an undercut wall to lock against the inclined end face of the support.

3. In a roll film developing apparatus, the combination with a developing tray, of a 65 film supporting member therein having film retaining devices on its under side and provided with a tortuous passage opening at its top through which developer may be poured upon the film. 70

4. In a roll film developing apparatus, the combination with a developing tray, of a film supporting member therein having parallel film guides on its under side adapted to hold a film strip by its edges and a channel above 75 and between the guides, said member being provided with a tortuous passage opening at its top and communicating with the channel to permit developer to be poured upon the film. 80

5. In a film roll developing apparatus, a film support having a longitudinal channel therein and converging film guides on opposite sides thereof adapted to hold a film strip by its edges in a curved position wherein it will be exposed to developer introduced into the channel. 85

ROBERT KROEDEL.
